UNITED STATES PATENT OFFICE

1,996,064

DOOR OPERATING DEVICE

James H. Crist, Ballston, Va.

Application August 11, 1933, Serial No. 684,729

2 Claims. (Cl. 268—62)

The invention relates to door operating means and particularly to devices adapted to be attached to ordinary swinging double doors, to insure uniform closing at the predetermined closed position. It is a specific purpose to present a construction in the door operating device that will enable the opening of one door through a greater arc than the other where required, and which will be adjustable to vary this difference to suit individual jobs.

Another object is to present a construction in closers which will operate the doors satisfactorily to insure proper overlap of the astragal or weather strip customarily applied to the vertical swinging edge of one door so as to overlie the other.

It is also an object to so perfect the invention that a stock form of equipment may be produced which will be adjustable to the various requirements of ordinary use without requiring special sizes or fittings while yet retaining the advantages above recited.

It is a purpose to enable the production of a device embodying the invention at an extremely low cost and which will be light in weight, efficient and durable in operation.

Additional objects, advantages and features of invention reside in the construction, arrangement and combination of parts involved in the embodiment of the invention as will appear from the following description and accompanying drawing, wherein,

Figure 1 is a top plan view of a door installation embodying my invention.

Figure 2 is a side elevation of the traveller and its mounting.

Figure 3 is a cross section of the traveller, showing the latch.

Figure 4 is a detail of the connection between the links and doors.

Figure 5 is a fragmentary bottom view of the connection of the links with the traveller.

There is illustrated a garage frame 10, including side members 11 and a door lintel 12 therebetween at one end. Doors 13—14 are hinged on respective sides of the frame 10, and these may be conventional doors hung in the conventional way. The right hand door 13 is adapted to move in advance of the other in closing and the door 14 is provided with an astragal strip 15 on its outer face at the swinging vertical edge, projecting beyond the vertical edge of the door to function as a weather strip in the customary way. The doors are shown as being of equal radius, but this is not essential. When closed they meet in abutment centrally of the door opening in the

frame 10, and in a common plane. On the lintel 12 and extending inwardly there is mounted a horizontal rectilinear rail 16, which may be a simple channel bar as in Fig. 3 with its channelled side uppermost, secured to the lintel at the middle of the latter and at right angles thereto. A support 17 for the inner or rear end of the rail 16 may be provided, if desired.

Slidable on the rail 16 there is a traveller 18. This consists simply in a sheet metal member bent 10 into U-shape to present two side plates 19 projecting a distance above the rail near the ends, these plates being transversely bored to receive the two pins 21 on which respective anti-friction wheels 20 revolve. These wheels are set between 15 and spaced from the plates 19 and are of a width to fit smoothly between the flanges of the channel bar 16.

Centrally of the bottom plate 22 of the traveller a downwardly projected stud 23 is provided, 20 tenoned and threaded at its extremity to receive a nut 24 and washer 25 thereabove.

Respective door opening links 26 and 27 are pivoted at their extremities on the doors 13 and 14 respectively, as will be described, and at their 25 inner ends on the stud 23. For this purpose, the links are each formed with a single aperture therethrough at their outer ends, and over their inner end portions are formed with a multiplicity of apertures 28 all of a size to receive the stud 30 30 23 alternatively therein. The inner ends of the links are crossed with appropriate apertures 28 alined and with the stud engaged through the alined apertures, a spring 29 being confined between the washer 25 and the links whereby the 35 latter are held on the stud and firmly against the plate 22 without liability of rattling. The outer end of each link is secured pivotally by a bolt 30 to an outstanding horizontal arm 31 consisting of a flat plate having a longitudinal series of apertures 32 therein, the arm being at right angles to the door as shown, and having a bracket arm 33 integral therewith bolted against the inner face of the door in a suitable location.

One link may be adjusted longer than the other, and also, if desired one of the brackets may be nearer the axis of the door if desired, in order that such door shall open further than the other, in case that be desired. And in such case the 50 link connected to that door is connected nearer the base of the arm 31 and the other link is connected at such distance from the base of the other arm 31 as will equal the difference in the 55 distances from the link pivots on the doors

to the stud 23, when the door is closed, as dotted in Figure 1.

The traveller has the end of one plate 19 extended and bent laterally outward at right angles to form a latch strike as at 34. Mounted on the inner side of the lintel 12 there is a spring-pressed latch bolt 35 slideable longitudinally of the lintel and held by its spring normally at the inner limit of its movement next the rail 16. It is formed with a bill 36 projecting into the path of the strike 34, the side of the bill in the direction of the traveller being inclined so that as the traveller strike 34 engages the bill the latter will be moved out of the path of the strike, retracting the bolt and permitting the strike to pass in front of the bill, which will then automatically engage by return of the bolt and prevent return of the traveller from open position until the latch is released. An operating cord 37 is connected to the bolt, and extended therefrom longitudinally outward beside the lintel 12, to a pulley 38, around which it is passed outwardly to the door thereadjacent to which it may be secured at a distance from the hinges, or it may be extended to any other place convenient for manual operation.

An outer spring anchor consisting of a horizontal angle bar 39 is secured on one door, having a longitudinal series of apertures in its projecting flange as at 39', and by means of a bolt 40 selectively engageable in these apertures a contractile helical wire door-closing spring 41 is connected to the door. An inner spring anchor plate 42 for this spring is mounted on the inner side of the lintel 12, at a distance from the hinge axis of the door which is ordinarily approximately one third the radius of the door, though this may be varied to suit special installations. The heavier doors will ordinarily operate better if the inner anchorage is an inch or more further from the pivot of the door. This anchor plate 42 is a broad horizontal plate secured to the lintel on or near a level with the under side of the lintel and the anchor 38 and is formed with a multiplicity of apertures spaced both transversely of the plate and longitudinally thereof. In the present instance there are three longitudinal series of such apertures in the plate, all spaced transversely of the plate so that there are six rows of three apertures transversely of the plate and three rows of six apertures longitudinally of the plate. The spring 41 is anchored to the plate 42 by means of a bolt 43 similar to the one 40 and selectively engageable in any of the apertures of the anchor plate 42.

By this construction of the spring anchorage, adjustments are attained by which the maximum tension, and also the progressive decrease of tension of the spring as the door closes may be varied

to suit different installations. The doors are opened manually in the present instance, though any power means for the purpose may be employed. The spring 41 closes the doors.

In the use of this invention the door being installed and equipped as described, when opened as indicated the strike 34 then engages the bill 36 of the latch 35, and passing in front of the latter is held against return until manual release of the latch. The door is then released and caused to close by a momentary pull on the cord 37, which releases the latch and permits the springs to move the doors to closed position. The cable 37 may of course be extended to a distant point conveniently for operation by a person in a motor vehicle.

I claim:—

1. A frame having a door way, doors pivoted thereon at respective sides of the doorway to swing to closed position with their swinging edges abutting, a guide mounted over said opening and extending inwardly therefrom, a traveller on said guide, extensible links pivoted thereon and connected to respective doors, the last named connection consisting of respective arms mounted fixedly on the inner sides of the doors near their meeting edges and the longitudinal axis of the arms projecting from the planes of the doors in the general direction of said guide when the doors are closed, and means to connect the extremities of the links pivotally to the respective arms, adjustable longitudinally of the arms, whereby the connection of each link and door may be adjusted toward and away from the plane of the door to compensate for differences in length of the links between the traveller and door connections when in closed positions, and whereby the connections with the doors may be near their swinging edges at all adjustments.

2. A door operating mechanism, consisting of two doors mounted to swing into abutting closed relation, a stationary guide mounted to extend inwardly from the doors when in closed position, a traveller thereon, links connecting respective doors with the traveller, the connection of each link with the traveller being individually adjustable longitudinally on the links, the connection of each link with its door consisting of an arm projected longitudinally from the inner side of the door near its vertical swinging edge and means to connect the link to the arm, adjustable longitudinally of the arm, whereby when said doors are closed the difference in the distances of the connections of the links from the plane of the doors will compensate for the difference in lengths of the links between the traveller and the door connections.

JAMES H. CRIST.
